UNITED STATES PATENT OFFICE

HORACE A. FOUTS, OF PORT ARTHUR, TEXAS, ASSIGNOR TO THE TEXAS COMPANY, OF NEW YORK, N. Y., A CORPORATION OF DELAWARE

PROCESS FOR CRACKING OILS

Application filed May 2, 1928. Serial No. 274,379.

This invention relates primarily to improvements in the manner of handling oil to be cracked, especially with relation to the zones in which the oil is subjected to heat. The invention has particular reference to a system in which hydrocarbon oil of relatively high boiling point is subjected to heat under considerable pressure in a coil, from which the oil is delivered to a drum or a plurality of drums and the vapors generated in the process are sent through suitable dephlegmating or fractionating apparatus, such as a bubble tower or the like, to separate the desired constituents, such as gasoline, from the heavier components which are condensed and recycled. In most systems of this kind it is customary to force the oil through the coil in the heating zone from the top to the bottom of the latter, this being from the cooler to the hotter portions of the coil. The heavier constituents of the generated vapors which are, as a rule, returned to the coil for further cracking are generally mixed with the fresh charge of oil before the latter is introduced into the coil.

By the present invention it is proposed to handle the oil in an improved manner, which may here be briefly outlined. It is first contemplated to raise the temperature of the charge of fresh oil as far as possible by employment of suitable heat exchangers through which the heat of the products resulting from the process, which would otherwise be wasted, may be utilized. For this purpose it is proposed to pass the charge first through a heat exchanger, which is suitably located in the vapor line above the fractionating tower. This arrangement not only provides for the desired conservation of the heat in the generated vapors, but it also serves to supply the desired cooling or regulating medium, in the form of refluxed material, for the operation of the tower. After leaving this heat exchanger, the fresh charge may be forced through a second heat exchanger, where it is adapted to receive additional heat from the tarry residues drawn from the bottom of the drum, or battery of drums, employed in the process. Upon leaving this second heat exchanger

the temperature of the oil will have been raised to a considerable degree and the burden placed upon the primary heating units will be greatly lessened. The charge is now preferably forced through a suitable economizer coil located in the path of the hot gasses generated in the main furnace which houses the main heating coil. From the outlet end of the economizer coil it is then contemplated to pass the oil through a section at the bottom or the hottest portion of the main heating coil. However, at a point just in advance of the inlet to this lower section of the heating coil, the fresh charge of oil is preferably merged with a quantity of the refluxed material which is returned from the base of the bubble tower or other dephlegmator or fractionator. The temperature of the two streams of oil merged at this point will be substantially the same and it will be considerably less than the usual temperature of the oil at the time it is sent through the hottest tubes of the heating coil. Upon leaving the lower section of this coil, the mixture of oil is preferably introduced into the top section of the main heating coil and is passed downwardly through the latter to the progressively hotter sections until its temperature has been raised to the desired point for introduction into one or more of a series of drums or stills where a relatively large volume of oil is maintained at a cracking temperature and under superatmospheric pressure. If desired, only one of these drums or stills may be employed, although it has been found preferable to employ a battery of three or four of them. External heat may be applied to the drums, if desired, for the purpose of offsetting the heat losses, although this is not essential and they may, if desired, be merely heat-insulated.

According to the present invention, the economizer unit and the main heating coil may, if desired, be constructed and arranged as distinct units or they may constitute merely separate sections of one continuous coil so that the latter is in effect divided into three sections—one the uppermost or coolest section, an intermediate section, and the bot-

tom or hottest section. The coil in all of these sections may, if desired, be constructed in the form of one single, continuous passage through which all of the oil must be passed in series. However, it is contemplated as preferable, in accordance with the present invention, to arrange and connect the tubes, which serve to form the coil, in a combination parallel-and-series arrangement; for example, the upper section, or economizer unit, 10 may consist of groups of three tubes arranged in parallel and connected by suitable headers to place successive groups of three tubes in series.

15 This will serve to provide three separate streams of oil in parallel relation through the upper section where the intensity of the heat is not so great and where the retarded movement thus brought about will not be harmful but, on the other hand, will provide a greater time period for bringing the temperature of the fresh charge up to that of the refluxed condensate. Upon leaving the upper section, these three separate streams 20 will preferably be merged by a suitable header into a single stream for passing the fresh charge, as well as the refluxed material subsequently joined with it, through the lower section of the coil in which the tubes 25 are preferably single-series connected. This arrangement will insure a very rapid flow of the oil through the lowermost tubes and will prevent to a large degree the deposition of carbon, which might otherwise result. 30 The tubes constituting the intermediate section of the coil may, if desired, be connected to form one single, continuous passage, although it has been found preferable to connect the upper or cooler portion of these tubes in such a way as to provide two parallel streams of oil, which are then preferably merged into a single stream for passage 35 through the lower or hotter portion of this intermediate section.

40 Many advantages arise from the handling of the oil in the manner indicated above. A primary advantage is the lengthening of the life of the lowermost tubes of the coil, which are subjected to the most severe outside temperature and are, in accordance with 45 this invention, subjected to a less severe inside temperature than is normally the case. Furthermore, the merging of the fresh charge and refluxed material prior to their 50 passage through this lower section serves to lighten the mixture which is passed through these tubes and thereby lessens the tendency to deposit carbon. By virtue of the arrangement of the tubes, partly in series and partly 55 in parallel, the desired velocity of the oil is maintained through the hottest section 60 of the coil while through the cooler sections where the liability to deposit carbon is less, a greater time element is provided for the 65 absorption of heat.

With the foregoing objects and advantages in view, one suitable form of the invention will now be described in greater detail with reference to the accompanying drawings which form a part hereof and in which— 70

Figure 1 illustrates schematically the general arrangement of one suitable form of cracking system embodying the present invention, and

Figure 2 illustrates schematically the arrangement and form of connection between the several tubes constituting a preferred form of the heating coil. 75

While one form of the invention, as applied to a cracking system, is disclosed in this case, and a modified or preferred form of coil is shown, it is to be understood that this disclosure is merely illustrative and that the invention is capable of application to a variety of other systems. 80

Referring now to Figure 1,—10 designates generally the entire heating coil consisting of three separate sections including an economizer section 11, an intermediate section 12, and a lower section 13, adapted to receive the greatest intensity of heat from the burner 14. Oil which has been heated in the several sections of the coil 10 by passage therethrough, in a sequence which will be explained hereinafter, is then passed by means of a line 15 to one or more of a series or battery of stills 16. In the form of apparatus illustrated, the heated oil may be split into three separate streams which may be led into the first three of the battery of stills or drums, although by means of the valves shown, this may be varied to suit the particular needs. The stills are preferably interconnected, both above and below the liquid level line, and the vapors generated in all of them are adapted to be carried by a pipe 17 to a suitable dephlegmator or fractionating tower 18. A portion of the vapors will be condensed in this tower and will collect in the base, from which they may be withdrawn by means of a pump 19 and recycled through the heating coil in a manner to be explained: those vapors which persist as such through the tower are carried into a refluxing condenser 20 and from the latter, beyond 90 to a final condenser and suitable collecting apparatus. Within the condenser 20 there is preferably located a coil 21 through which the incoming fresh charge of oil is first passed in heat exchange relation with the vapors passing through this condenser. In this way the temperature of the fresh charge is raised to a certain extent and at the same time a portion of the vapors are 95 condensed and returned to the top of the fractionating tower by means of the backtrap line 22, to serve as a cooling and regulating medium therefor. If desired, a portion or all of the charge may be by-passed by a proper manipulation of the valves shown. 100 105 110 115 120 125 130

From the coil 21 the fresh charge is passed by means of a pipe 23 to another coil 24 which is mounted in a container 25. This container is in the path of flow of the tarry residues which will be withdrawn from time to time from the series of stills 16 through the pipes 26, so that a second heat exchange is provided between these residues and the fresh oil. Beyond the container, the residue

10 um may be passed through a suitable cooling tank 27 and on to any suitable storage tanks.

In its passage through the coil 24, the fresh charge of oil will have its temperature raised a second step above its initial temperature 15 and it may now be passed by means of a line 28 to the inlet end of the economizer section of the coil 10. After traversing the tubes of the economizer, the charge is passed by means of a line 29 to a point 30 near the lower section 20 of the heating coil where it is merged with the condensate which is being pumped by means of the pump 19 from the base of the fractionating tower. The mixture of fresh oil and returned condensate is then 25 forced through a line 31 to the lowermost tubes forming section 13 of the coil, which is subjected to the highest temperature within the furnace. As many tiers or rows of the tubes at the bottom of the coil may be connected in series as desired to form the lowermost and hottest section of the coil. After 30 leaving the upper end of this section, the oil is passed through a line 32 into the top of a series of tubes forming the intermediate section 12 of the coil, from the lower end of which the heated mixture of fresh charge and condensate is passed, as before explained, by means of the line 15 into one or more of the 35 battery of stills 16.

40 In connection with the foregoing description, the heating coil has been regarded as comprising, in all of its sections, a single passage through which all of the oil is passed in series. If desired, the tubes which go to make 45 up the coil may be so connected as to provide a number of parallel channels through which the oil may be passed. Figure 2 discloses one suitable form of connection between the tubes for this purpose to provide a relatively slow 50 movement of the oil through the upper or economizer section, a very rapid flow of the oil through the lowermost or hottest section and different speeds of flow, varying from a relatively slow speed to the maximum speed 55 through the intermediate section. In this figure, there is disclosed a furnace 33 in which the coil is mounted and which is provided with any suitable form of burner 34 for supplying heat to the tubes. Within the 60 furnace there is arranged, to form the coil, a series of tubes 35 placed horizontally and in a plurality of rows. Any number of rows of these tubes may be selected to form the economizer section and in this section suitable 65 headers 350 may be provided for joining the

ends of each group of three tubes with corresponding ends of an adjacent group of three tubes. The arrangement is such that the headers at the opposite ends of the tubes are staggered with relation to each other and the tubes of the entire row are thus divided into groups of three, which are series-connected and through which the oil passes in three parallel streams. For the purpose of conducting the oil from an upper to a lower row of tubes, a suitable header 36 may be provided and this may serve to join a group of three tubes in each of the two rows. If desired, there may be provided, in lieu of the header 36, three individual return bends each connecting one of the tubes of an upper row with one of the tubes of a next lower row.

After the charge has been made to pass in three parallel streams through the sets of tubes in this manner, in any desired number of rows forming the economizer section, a header joining the last three tubes of the lowermost of the economizer rows may be connected to a line 37 which, at its lower end, joins the pipe 31 at the juncture point 30 where the fresh charge and returned condensate are merged. The pipe 31 will preferably be connected only to a single tube in the lowermost row while each of the tubes of this row will be joined successively at one end to the next adjacent tube by means of suitable headers or return bends 38 so as to form one continuous channel. Several of the lowermost rows of tubes may be connected together by headers 39 to form a single continuous coil of any desired number of rows of tubes. The end tube of the uppermost row of the lower section of tubes will preferably be connected by a pipe 40 to a header 400 joining a pair of tubes in the uppermost row of the intermediate section. Suitable headers 41 are then provided in this row for successively joining one end of each pair of tubes to the next adjoining pair so as to form two continuous parallel channels for the oil and this arrangement may be continued down through any desired number of rows of tubes. Headers 42 may be provided to join an end pair of tubes in one row with the corresponding end pair of the next lower row, or, if desired, the pairs of tubes in the adjacent rows may be connected by a pair of single headers or return bends. After traversing a suitable portion of the intermediate section of the coil in a pair of parallel streams, the oil will preferably be merged into a single stream by means of a suitable header 43 which serves to connect the end pair of tubes in the lowermost row of this portion of the tubes with a single end tube of a next lower row.

Suitable headers or return bends 44 are then provided in this row to successively join adjacent tubes of this row in series to form one continuous passage. A similar

header 45 may be provided to join the end tubes of adjacent rows of this section of the coil so that any suitable number of rows of tubes may be employed in this relatively hot portion of the intermediate section. From one end of the lowermost row of tubes in this section, the oil is then passed into the pipe 15 leading to the battery of stills 16.

In the operation of the system which has been described, the conditions as to temperature and pressure at the various stages may be varied within very wide limits. Suitable ranges may be mentioned here purely for the purpose of illustration and without any intention of limiting the scope of the invention. As for pressure, it is contemplated as preferable to maintain a substantially uniform condition throughout the system to a point beyond the final condenser subject to such drops as may be brought about by the friction in the various parts. This pressure will preferably range between 100 lbs. and 500 lbs., or even higher, in the coil and may drop from 25 lbs. to 50 lbs. through the system. If desired, a substantial drop in pressure might well be provided between the coil and the drum or series of drums and/or between the drums and the fractionating apparatus. Suitable temperature ranges might be such as to provide a charge to be introduced into the economizer coil at a temperature between 400° and 550° F. and leaving the economizer coil at between 500° and 700° F. The hottest section of the coil might well be subjected to temperatures between 1200° and 1800° F. and might serve to raise the temperature of the oil to between 600° and 800° F. while in the intermediate section of the coil the oil might be raised to a temperature between 750° F. and 900° F.

It is believed that the intended mode of operation of the system has been set forth to a sufficient extent in the foregoing description so that it will not be necessary to provide a résumé of the operation at this point. While an admirable form of the invention has been disclosed herein, it is to be understood that it is capable of various modifications without departing from the spirit of the invention and it is desired to be limited only in this respect by the scope of the claims which follow:

What I claim is:

1. The method of cracking hydrocarbon oils which comprises flowing the oil through the lowest temperature section of a heating zone in a plurality of streams in parallel, then passing the heated oil in a single stream through the hottest section of the heating zone, then passing the oil through an intermediate section of the heating zone in a plurality of streams in parallel, separately withdrawing vaporous products and condensing the heavier constituents thereof, and returning the resulting condensate to the stream of

oil flowing through the said hottest section of the heating zone.

2. The method of cracking hydrocarbon oils which comprises flowing the oil through the lowest temperature section of a heating zone in a plurality of streams in parallel, then passing the heated oil in a single stream through the hottest section of the heating zone, then passing the oil through an intermediate section of the heating zone in a plurality of streams in parallel, thereafter uniting the oil streams into a single stream and passing the said stream through a heating zone of higher temperature than that in the immediately preceding section of the heating zone, separately withdrawing vaporous products and condensing the heavier constituents thereof, and returning the resulting condensate to the stream of oil flowing through the said hottest section of the heating zone.

3. The method of cracking hydrocarbon oils which comprises flowing the oil through the lowest temperature section of a heating zone in a plurality of streams in parallel, then passing the heated oil in a single stream through a radiant heat section of the heating zone, then passing the oil through an intermediate section, separately withdrawing vaporous products and condensing the heavier constituents thereof, and returning the resulting condensate to the stream of oil flowing through the radiant heat section of the heating zone.

4. The method of cracking hydrocarbon oils which comprises flowing the oil through a relatively low temperature heating zone in a plurality of streams in parallel, then passing the heated oil in a single stream through a radiant heat zone, thereafter passing the oil through a heating zone in a plurality of streams in parallel maintained at a temperature intermediate the temperature of the said first and second named heating zones, separately withdrawing vaporous products and condensing the heavier constituents thereof, and returning the resulting condensate to the stream of oil flowing through the said radiant heat zone.

5. The method of cracking hydrocarbon oils which comprises flowing the oil through a relatively low temperature heating zone in a plurality of streams in parallel, then passing the heated oil in a single stream through a relatively high temperature heating zone, thereafter passing the oil in a plurality of streams in parallel, through a heating zone maintained at a temperature intermediate the temperature of the said first and second named heating zones, separately withdrawing vaporous products and condensing the heavier constituents thereof, and returning the resulting condensate to the stream of oil flowing through the said high temperature zone.

6. The method of cracking hydrocarbon oils which comprises flowing the oil through a relatively low temperature heating zone in a plurality of streams in parallel, then passing the heated oil in a single stream through a relatively high temperature heating zone, thereafter passing the oil in a plurality of streams in parallel through a heating zone maintained at a temperature intermediate the temperature of the said first and second named heating zones, thereafter uniting the streams into a single stream and passing the said stream through a heating zone of higher temperature than said third-named heating zone and of lower temperature than said second-named heating zone, separately withdrawing vaporous products and condensing the heavier constituents thereof, and returning the resulting condensate to the stream of oil flowing through the said high temperature zone.

In witness whereof I have hereunto set my hand this 21st day of April, 1928.

HORACE A. FOUTS.
